UNITED STATES PATENT OFFICE

FRANK W. ANDREWS, OF FORT WAYNE, INDIANA, ASSIGNOR, BY MESNE ASSIGNMENTS,
TO FRIGIDAIRE CORPORATION, A CORPORATION OF DELAWARE

REFRIGERATING APPARATUS

Application filed December 31, 1927. Serial No. 243,965.

The present invention relates to improvements in refrigerating apparatus and more particularly the refrigerating element intended for use in mechanically refrigerated cabinets.

It is an object to simplify the construction of the heat exchange portions of the element and to dispense with the use of refrigerant conducting pipes therein without detracting from the freezing efficiency of the element.

It is another object of the present invention to improve the construction of refrigerating apparatus and more particularly the type in which a cold producing element such as an evaporator and brine tank associated therewith is supported within a refrigerator cabinet.

It is a further object of the invention to provide an element whose exterior presents a minimum of protruding parts and which therefore may easily be cleaned.

Further objects and advantages of the present invention will be apparent from the following description, reference being had to the accompanying drawings wherein a preferred form of the present invention is clearly shown.

In its general aspects the improved element comprises a tank or casing in one portion of which is immersed a refrigerant containing heat exchange device, another portion thereof being arranged to embrace a compartment adapted to hold substances to be frozen, the heat exchange between the refrigerating member and the chamber being effected by means of a suitable liquid aided by metallic conducting members attached to the compartment and disposed in heat transmitting relation to the liquid and said refrigerating member.

In the drawings:

Fig. 1 shows a front view of a cabinet equipped with the improved refrigerating element of the invention;

Fig. 2 is a side view partly in section of the element; and

Fig. 3 illustrates a front view also in section of the refrigerating element.

Referring in detail to the drawings the improved element comprises a container 10

preferably formed of sheet metal and adapted to hold a liquid, an opening 12 being provided for filling the container and a suitable plug being used for hermetically sealing the same.

The tank 10 is provided with a chamber 11 preferably in the lower portion, likewise made of sheet metal and so located as to be substantially immersed in and surrounded by the liquid contained in the tank 10 except at the front portion which is open and which faces the front of the refrigerator cabinet.

In another portion of the container 10 is mounted a refrigerant containing heat exchange device such as an expansion coil or flooded chamber element. In the preferred embodiment of the invention a flooded chamber element is used and comprises a chamber 15 built in the form of a receiver for a suitable refrigerant such as sulphur dioxide. This refrigerant is present in the chamber 15 in the form of liquid. The arrangement shown constitutes a so-called "flooded system" in which a considerable body of liquid is contained in the chamber 15. The abstraction of heat from the liquid in the tank 10 causes the sulphur dioxide to vaporize, the gaseous refrigerant being withdrawn from above the liquid through a pipe 17 leading to the compressor (not shown).

The refrigerant is conducted to the chamber 15 through pipe 16, the level of the liquid in said chamber being controlled by a needle valve operated by a float 17a which rides on the surface of the refrigerant.

The compartment 11 above referred to extends into the tank through one of the vertical walls thereof, preferably the front wall, and among other effects serves to increase the surface area of the tank by insuring the absorption of heat by the liquid in the tank as well as forming an enclosure or freezing chamber for the reception of substances to be congealed.

Suitable shoulders or the like 14 are provided within said chamber and adapted to receive plates 23 which divide the chamber into a plurality of compartments each containing a drawer or tray 13. These trays 13 are used for holding the substances to be congealed and are provided with fronts 10a

20 arranged to provide a symmetrical appearance. The trays may be provided with suitable handles as at 31. Attached to the walls of the sleeve 11 and in good thermal contact therewith are a plurality of heat conducting members 21. These preferably consist of metal bands which are bent up as at 22 so as to terminate somewhat as radii extending from the refrigerant containing member but 10 distinguished by the fact that they are not actually attached to said member but come substantially in contact therewith and in heat transmitting relation therewith. It will be appreciated that the members or rods may be 15 shaped in different ways and that they may extend around the member 15 in various ways. In the preferred embodiment of the invention among other things to facilitate assembly of the device and owing to the efficiency of the 20 immersion liquid present in the container 10 the ends 22 of the heat conducting members 21 are not directly attached to the refrigerant containing chamber 15 but are brought very close to the same. This construction 25 facilitates assembly of the apparatus since the chamber 11 and its radiating fins or members 21, 22 may be positioned in the tank or container 10 whereupon the refrigerant containing member 15 may be inserted.

30 The front of the member 15 is preferably provided with a cover 24. This cover as well as the exterior of the tank 10 and the fronts 20 of the trays should preferably be finished with a cleanable attractive impervious and 35 noncorrodible surface such as porcelain or the like. When ready for use the casing 10 is filled with a substance such as brine which has great holdover capacity and which will not congeal. This serves to conduct the heat 40 from the refrigerant containing device to the compartment 11, this transfer of heat being augmented by the metal conducting members 21, 22 which extend in close proximity to the device 15 and preferably below said device 45 at which portion the brine is the coldest. A plug 12 is provided for admitting brine to the tank 10.

Since the metal members 21, 22 are in intimate contact with the walls of the compartment 11, a freezing zone is provided by these members in which substances may be rapidly congealed.

Referring to Fig. 1 in which the improved element of the invention is shown installed in 55 a refrigerator it will be observed that the refrigerator comprises a cabinet having thermally insulated walls 25 provided with an impervious lining 26. Shelves 27 are provided for the reception of objects to be cooled. 60 The element is mounted in the cabinet as by hanger brackets 28 or the like. A suitable drip pan 29 may be provided for catching the moisture resulting during defrosting. The compressor used for operating the element 65 may be disposed in the bottom compartment

of the cabinet here shown covered with a louvered ventilating plate 30.

While the form of embodiment of the invention as herein disclosed, constitutes a preferred form, it is to be understood that other forms might be adopted, all coming within 70 the scope of the claims which follow.

What is claimed is as follows:

1. A refrigerating device for mechanically refrigerated cabinets, comprising a container 75 for holding a heat transfer fluid, a support for an ice tray within the container, metallic heat conducting means secured in thermal relation with the support, and a refrigerant-containing heat exchange element insertable into said container and arranged in close proximity to said means without touching same.

2. A refrigerating device for mechanically refrigerated cabinets, comprising a container 85 for holding a heat transfer fluid, a support for an ice tray within the container, metallic heat conducting means arranged in thermal relation with the support and a refrigerant-containing heat exchange element extending 90 in close proximity to said means without touching same and removable from said container without disturbing said means.

3. A refrigerating device for mechanically refrigerated cabinets, comprising a container 95 for holding a heat transfer fluid, a freezing chamber within the container, a plurality of fins secured in intimate thermal contact with said chamber, and a refrigerant-containing heat exchange element insertable into said container and arranged in close proximity to said means without touching same.

4. A refrigerating device for mechanically refrigerated cabinets, comprising a container 105 for holding a heat transfer fluid, a freezing chamber within the container, a plurality of fins secured in intimate thermal contact with said chamber, and extending outwardly and upwardly therefrom, and a refrigerant-containing heat exchange element insertable into 110 said container and arranged in close proximity to said means without touching same.

5. A refrigerating device for mechanical refrigerators comprising a container, a support for an ice tray within said container, a cooling element within said container, metallic heat exchange means connected with said support and extending in close proximity to the cooling element without touching the same. 115

6. A refrigerating device for mechanical refrigerators comprising a container, a support for an ice tray within said container, a cooling element within said container, fins connected with said support and extending 120 in close proximity to the cooling element without touching the same.

In testimony whereof I hereto affix my signature.

FRANK W. ANDREWS.
